Specification for Design.

Patented May 4, 1920.

Application filed December 3, 1919. Serial No. 342,270. Term of patent 14 years.

To all whom it may concern:

Be it known that I, GEORGE C. LARGE, a citizen of the United States of America, residing at Mahoningtown, in the county of Lawrence and State of Pennsylvania, have invented a certain new, original, and ornamental Design for a Vehicle-Tire, of which the following is a specification, reference being had to the accompanying drawing, forming part thereof.

Fig. 2 shows a transverse section of Fig. 1.

I claim:

The ornamental design for a vehicle-tire, as shown.

In testimony whereof I affix my signature.

GEORGE C. LARGE.
